CLAIM

The ornamental design for a combined artist's brush holder and cleaning vessel, as shown and described.

DESCRIPTION

FIG. 1 is a perspective view of a combined artist's brush holder and cleaning vessel showing my new design;

FIG. 2 is a top plan view thereof;

FIG. 3 is a front elevational view thereof shown without the cover;

FIG. 4 is a right side elevational view of FIG. 3, the left side being a mirror image thereof;

FIG. 5 is a rear elevational view thereof;

FIG. 6 is a bottom plan view thereof;

FIG. 7 is an exploded perspective view of FIG. 1; and

FIG. 8 is a top plan view thereof, shown without the cover.
